UNITED STATES PATENT OFFICE.

WALTER H. SEAVEY, OF KEARSARGE, NEW HAMPSHIRE.

SAW RIG.

Application filed March 16, 1925. Serial No. 16,009.

To all whom it may concern:

Be it known that I, WALTER H. SEAVEY, a citizen of the United States, residing at Kearsarge, in the county of Carroll and 5 State of New Hampshire, have invented new and useful Improvements in Saw Rigs, of which the following is a specification.

This invention relates to saw rigs and has for an object the provision of a rig 10 which is simple in construction, easy to operate and may be readily transported from place to place, the invention being especially adapted for sawing cord wood.

Another object of the invention is the 15 provision of novel means for feeding the wood to the saw, whereby operation of the latter will exert a downward pressure upon the wood and greatly facilitate the operation of sawing, so that a given amount of 20 material may be sawed in a relatively short time and with a minimum amount of labor.

Another object of the invention is the provision of novel means for adjusting the 25 level of the feeding table so that the latter may be properly adjusted for use even though the rig is out of level.

With the above and other objects in view, the invention further includes the following novel features and details of construction, to be hereinafter more fully described, 30 illustrated in the accompanying drawings and pointed out in the appended claims.

In the drawings:—

Figure 1 is a side elevation of a saw rig 35 constructed in accordance with the invention.

Figure 2 is a front view of the same.

Figure 3 is a top plan view.

Figure 4 is a longitudinal sectional view.

40 Referring in detail to the drawings wherein like characters of reference denote corresponding parts, the rig is shown as comprising a supporting frame, the latter including spaced sills or runners 10 from 45 which rise standards 11. These standards are connected by longitudinal timbers 12 and transverse connecting bars 13. A rigid frame is thus provided which may be supported in any manner such as wheels or

50 runners, the sills 10 serving as the latter. If desired the frame may be supported upon a bench or table, according to the character of the work for which it is intended.

55 Mounted in bearings 14 supported upon the sills 10 is a shaft 15 and secured upon this

shaft is a saw blade 17. Also secured upon the shaft 15 is a pulley 18 which is driven by a belt 19 and the latter may be operated from any suitable source of power such as a motor or engine, either mounted upon 60 the supporting frame or mounted separately therefrom. The belt is preferably provided with an automatic tightener shown in the form of a roller 20 which engages the belt, and which is carried at one end of an 65 arm 21, the opposite end of which is pivotally mounted upon the frame as shown at 22.

Supported by the frame just described is a feeding frame, the latter including spaced 70 parallel substantially horizontally disposed beams 23 to the front ends of which is secured a table 24 upon which the material is placed to be fed to the saw. This table is transversely slotted as shown at 25 to receive 75 the saw and carries a guard 26 for the protection of the operator. Pivotally secured adjacent the front ends of the beams 23 are the lower ends of hanger bars 27. The upper ends of these bars are pivotally secured to 80 the timbers 12 through the medium of a rod 28, the outer ends of which extend through slots 29 provided in the timbers 12. The point of connection between the hanger bar 85 27 and the timbers 12 may thus be regulated by moving the rod 28 in the slots 29. The rear ends of the beams 23 have pivotally secured thereto the lower ends of rear hanger bars 30, the upper ends of which are pivotally secured to the timbers 12 as shown at 90 31. The points of connection of the upper ends of the bar 30 are in advance of the points of connection of the lower ends of these bars so that the tendency of the feeding frame just described will be to move the 95 table 24 away from the saw blade 17.

The position of the table 24 with relation to the blade 17 is such that when work upon the table is fed toward the saw the latter will engage the work in such position as to exert a downward pressure so that there will be no tendency of the work to raise from the table. The operation of sawing will thus be materially assisted.

Mounted in bearings 32 provided in the bars 13 is a longitudinally disposed threaded rod 33. Mounted upon and threadedly engaging this rod is a nut 34. Rods 35 have one of their ends secured to the nut 34 while the opposite ends of these rods are secured 105 110

to the front hanger bars 27 as indicated at 36, so that by rotating the threaded rod 33 the nut will be moved longitudinally of the rod and will carry with it the upper ends 5 of the hanger bars 27 so as to regulate the pivotal positions of these rods. The threaded rod 33 is preferably provided with an operating handle 37.

By changing the pivotal points of the 10 upper end of the hanger bars 27 the position of the table 24 may be regulated so that the said table may be leveled even though the supporting frame is out of level.

The invention is susceptible of various 15 changes in its form, proportions and minor details of construction and the right is herein reserved to make such changes as properly fall within the scope of the appended claims.

Having described the invention what is 20 claimed is:—

1. A saw rig comprising a supporting frame, a saw blade mounted for rotation thereon, means whereby the blade may be driven, a feeding frame comprising spaced 25 substantially horizontally disposed beams, a feeding table secured to the front ends of the beams and normally spaced from the saw, front hanger bars having their lower ends pivotally secured to the beams and their 30 upper ends pivotally supported in the supporting frame, rear hanger bars having their lower ends pivotally secured to the lower ends of the beams and their upper ends pivotally

secured to the supporting frame in advance of the pivotal connections of their lower 35 ends, whereby the table will normally swing in a direction away from the saw and means for regulating the point of connection of the front hanger bars and the supporting frame.

2. A saw rig comprising a supporting 40 frame, a saw blade mounted for rotation thereon, means whereby the blade may be driven, a feeding frame comprising spaced substantially horizontally disposed beams, a feeding table secured to the front ends of the 45 beams and normally spaced from the saw, front hanger bars having their lower ends pivotally secured to the beams, a slidable pivotal connection between the upper ends 50 of said bars and the supporting frame, rear hanger bars having their lower ends pivotally secured to the rear ends of the beams and their upper ends pivotally secured to the supporting frame in advance of the pivotal 55 connections of their lower ends, whereby the table will normally swing in a direction away from the saw, a threaded rod extending longitudinally of and mounted in bearings carried by the supporting frame, a nut mounted upon the rod and rigid means connecting the nut and front hanger bars, whereby rotation of the rod will regulate the point of pivotal connection between the front bars and said supporting frame.

In testimony whereof I affix my signature.
WALTER H. SEAWEY.
